FLEXIBLE SUSPENSION SYSTEM FOR HOME APPLIANCE

Aman Ullah Khan, Benton Harbor, Mich., assignor to
Whirlpool Corporation, a corporation of Delaware

Filed Apr. 28, 1961, Ser. No. 106,261

6 Claims. (Cl. 248—18)

This invention relates to a suspension system for the tub of a washing machine.

In washing machines and particularly automatic washing machines the wash water and rinse water are supplied to the tub of the machine automatically and the washing and rinsing cycles are automatically controlled. A washing machine of this type customarily contains a basket rotatable about a central axis and an agitator movable about the central axis. During the washing operation there is a period when the agitator moves and a period when the basket which is inside the tub and in which the clothes are contained is rotated at high speed in order to extract water from the clothes by centrifugal force.

These actions cause the tub which contains the basket and agitator to be subjected to varying forces including torsional forces and vibration forces. These forces are particularly severe in an automatic washing machine of the type described, as customarily the tub is mounted on a floating platform and the driving mechanism for the agitator and the basket are also mounted on the platform.

An undesirable condition in automatic washing machines of the type described occurs when these torsional and vibrational forces are transmitted from the rotating basket and supporting floating platform to the cabinet and frame structure through the suspension members. When these forces are severe, the cabinet and frame structure receive sufficient forces to vibrate the cabinet and possibly to cause it to walk across the floor.

The present invention provides a suspension system for resisting the forces set up in the tub and associated parts including torsional forces, vibration forces and the like.

One of the features of this invention therefore is to provide an improved suspension system for the tub of a washing machine in which the tub is subjected to forces tending to move the tub relative to the machine including torsional forces and vibration forces.

Other features of the invention will be apparent from the following description of one embodiment thereof as illustrated in the accompanying drawings. Of the drawings:

FIGURE 1 is a side elevational view partially broken away of a portion of an automatic washing machine embodying the invention and a second partially broken away portion of the machine embodying the base member.

FIGURE 2 is a plan view partially broken away of the machine of FIGURE 1.

FIGURE 3 is a view of a second embodiment of a suspension member.

A washing machine of the same type as discussed herein is disclosed in Geldhof and Ringer Patent 2,347,190 assigned to the same assignee as is the present application. As in this patent, the washing machine of this invention includes a tub 10 located within a cabinet 11, of which only a portion is shown in the drawings, and a basket 12 and an oscillatable agitator 13 located in the tub 10.

The tub 10 and thus the basket 12 as well as the agitator 13 are mounted on a floating base member or platform 14. Base member 14 is made up of two formed circular sheet metal plates 14a and 14b. Plate 14a has an upwardly formed dome to allow a substantial space 14c between plate 14a and the substantially flat plate 14b, when welded together. This space or cavity can be used to receive ballast material, before welding, to add mass to

2

the floating base structure. By increasing the mass of the base member 14, the inertia of this assembly and consequently the vibratory force necessary to move it through a predetermined amplitude, is increased. Therefore, the suspension system will tolerate a larger off balance mass. This platform also supports the driving portions of the washing machine used to oscillate the agitator 13 and rotate the basket 12 including the electric motor 15.

The oscillation of the agitator 13 and the rotation of the basket 12 set up forces in the platform, and thus the tub 10, including torsional forces tending to twist the tub and associated parts about the vertical central axis and vibration forces tending to cause the entire structure to vibrate. The improved suspension system of this invention successfully stores energy imparted to it by the vibrational and torsional forces sensed by the base member 14 and releases practically all the stored energy back to the base member rather than transmitting it to cabinet 11. Therefore, by supporting base member 14 and its associated parts with sufficiently flexible suspension members such as strips 21, an isolated condition of the tub and basket structure can be approximated and only the small forces necessary to overcome the resistance of the suspension member will be transmitted to cabinet 11. These small forces are not objectionable and can be tolerated.

The suspension system of this invention includes a supporting structure here shown as an octagonal frame 16 within the cabinet 11 and extending around the tub 10. This frame 16 is provided with a plurality of flanges 17 arranged around the central axis 18 of the tub 10, basket 12 and agitator 13. In the illustrated embodiment, there are three of these flanges 17 spaced approximately 120° apart; however these flanges 17 may assume various desired combinations of spacing around the frame 16. As can be seen from FIGURE 1, the flanges 17 are above the top 19 of the tub 10 and spaced outwardly therefrom. The base member or platform 14 is provided with three outwardly and upwardly extending flanges 20 that extend beyond the outer periphery of the tub 10 with each flange 20 being located substantially beneath but inwardly of an upper flange 17. Base member 14 may also include the previously mentioned ballast material.

Extending between each flange 17 and the corresponding flange 20 is a suspension member 21 in the form of an elongated metal strip having an upper end 22 fixedly attached across its entire width to the flange 17 as by a plurality of bolts and a lower end 23 fixedly attached across its entire width to a flange 20 as by a plurality of bolts 24. Each end 22 and 23 is clamped to its respective flange as by means of a clamping block illustrated at 25.

In the embodiment of FIGURES 1 and 2, each metal strip 21 is twisted 180° about its longitudinal axis so as to laterally deform strips 21 about said axis between the end portions 22 and 23 and to accommodate controlled flexing of strip 21 in those parts of the strip between the ends and the first nodes, that is, points 21a and 21b and 21b and 21c of FIGURE 1. Therefore, bending can take place, using for example strip 21 of embodiment 1, from 21a to 21b in any family of planes in the second and fourth quadrants of a circle scribed on a plane perpendicular to and having as its center the longitudinal axis of strip 21 and from 21b to 21c in any family of planes in the first and third quadrants of said circle.

This means of support accommodates free movement of platform 14 and tub 10 in a plane defined by the points of connection of the lower ends of strip 21 with platform 14.

In the embodiment of the metal strip suspension member 26 of FIGURE 3, the strip is provided with a pair of side flanges 27 extending on either side of the center

of the strip toward the attaching ends 28 and 29. The side flanges 27 which provide a stiffening effect terminate short of the ends 28 and 29 with the strip being twisted as indicated at 30 between the ends of the flanges and the attaching ends 28 and 29 of the strip. The stiffening flange 27 provides the same function as several twists of strip 21, i.e., both the stiffening flange 27 and the twisting of strip 21 give compressive strength to the suspension members.

From the above description it can be seen that each of the suspension members is twisted to obtain the flexibility needed for bending in any family of planes through and parallel to the longitudinal axis of strip 21 and any untwisted portion as illustrated in the embodiment of FIGURE 3 is provided with a longitudinal stiffening flange.

The suspension system of this invention provides a number of advantages not heretofore present in suspension systems for washing machine tubs of this type. Thus, because the suspension strips suspend the tub and associated parts in tension, the strips are small in cross sectional area and take up only a small amount of space thereby helping to conserve space for the ultimate user of the machine. This permits using a smaller cabinet to enclose a tub of any given size. Furthermore, because each suspending metal strip is a single integral unit with no welds, they are easy and not expensive to make and to install. Furthermore, without the welds of former apparatus they are stronger and safer.

Having described my invention as related to the embodiments shown in the accompanying drawings, it is my intention that the invention be not limited by any of the details of description, unless otherwise specified, but rather be construed broadly within its spirit and scope as set out in the accompanying claims.

I claim:

1. In a washing machine having a tub subjected to forces tending to move the tub relative to the machine including torsional forces and vibration forces, a suspension system comprising: a supporting structure; and a plurality of elongated suspension members for suspending said tub from said structure each having an upper end fixedly attached to said supporting structure and a lower end arranged to be operatively and fixedly attached to said tub, each of said suspension members comprising an elongated metal strip having a longitudinal axis and laterally deformed in areas about said axis for at least a portion of its length to facilitate flexing of said suspension members and movement of said tub in all directions in a plane passing through the lower ends of said suspension members.

2. In a washing machine having a tub subjected to forces tending to move the tub relative to the machine including torsional forces and vibration forces, a suspension system comprising: a base member for mounting said tub; a frame arranged to extend around the tub and having an upper portion located above said base member; and a plurality of elongated suspension members suspending said base member and thus said tub from said frame, each suspension member having an upper end fixedly attached to said frame and a lower end fixedly attached to said base member, each of said suspension members comprising an elongated metal strip having a longitudinal axis and twisted about said axis for at least a portion of its length to facilitate flexing of said suspension members and movement of said tub in all directions in a plane passing through the lower ends of said suspension members.

3. In a washing machine having a tub subjected to forces tending to move the tub relative to the machine including torsional forces and vibration forces, a sus-

ension system comprising: a base member for mounting said tub; a frame arranged to extend around the tub and having an upper portion located above said base member; and a plurality of elongated suspension members suspending said base member and thus said tub from said frame, each suspension member having an upper end fixedly attached to said frame and a lower end fixedly attached to said base member, each of said suspension members comprising an elongated metal strip having a longitudinal axis and twisted about said axis for at least a portion of its length and for at least about 90° to facilitate flexing of said suspension members and movement of said tub in all directions in a plane passing through the lower ends of said suspension members.

4. In a washing machine having a tub subjected to forces tending to move the tub relative to the machine including torsional forces and vibration forces, a suspension system comprising: a base member for mounting said tub; a frame arranged to extend around the tub and having an upper portion located above said base member; and a plurality of elongated suspension members suspending said base member and thus said tub from said frame, each suspension member having an upper end fixedly attached to said frame and a lower end fixedly attached to said base member, each of said suspension members comprising an elongated metal strip having a longitudinal axis and twisted about said axis for at least a portion of its length and for at least about 90° to facilitate flexing, and an untwisted portion between said ends provided with a longitudinal stiffening flange resisting flexing.

5. In a washing machine having a tub subjected to forces tending to move the tub relative to the machine including torsional forces and vibration forces, a suspension system comprising: a base member for mounting said tub; a frame arranged to extend around the tub and having an upper portion located above said base member; and a plurality of elongated suspension members suspending said base member and thus said tub from said frame, each suspension member having an upper end fixedly attached to said frame and a lower end fixedly attached to said base member, each of said suspension members comprising an elongated metal strip having a longitudinal axis and twisted about said axis between said ends for at least about 90°.

6. In a washing machine having a tub subjected to forces tending to move the tub relative to the machine including torsional forces and vibration forces, a suspension system comprising: a base member for mounting said tub; a frame arranged to extend around the tub and having an upper portion located above said base member; and a plurality of elongated suspension members suspending said base member and thus said tub from said frame, each suspension member having an upper end fixedly attached to said frame and a lower end fixedly attached to said base member, each of said suspension members comprising an elongated metal strip having a longitudinal axis and a longitudinal stiffening flange extending on either side of the center of said strip, said strip being twisted about said axis between said flange and said ends.
